UNITED STATES PATENT OFFICE.

JAMES J. LAWLER, OF MOUNT VERNON, NEW YORK.

DESIGN FOR AN AIR-CHAMBER.

SPECIFICATION forming part of Design No. 31,191, dated July 11, 1899.

Application filed June 13, 1899. Serial No. 720,415. Term of patent 7 years.

To all whom it may concern:

Be it known that I, JAMES J. LAWLER, a citizen of the United States, and a resident of Mount Vernon, in the county of Westchester 5 and State of New York, have invented a certain new and original Design for Air-Chambers, of which the following is a specification, reference being had to the accompanying drawings, forming part thereof.

- 10 Figure 1 is a front elevation of my new design, and Fig. 2 is a plan view.

My design consists of a cylindrical body A, open at its base and surmounted by a semi-spherical dome B. Between the body and dome an annular half-round bead b is used to define or break the plain appearance. Two perforated flat strips C extend from the back of the cylindrical body at a point about half-way up from the base, said strips being on a 15 20 straight line extending an equal distance from

the point on the periphery where line intersects circle, as shown in Fig. 2. On the periphery of the cylinder, near its base and facing the front, a tubular extension D is placed. The lower end of the cylinder terminates in 25 an annular half-round bead e, thus completing the design.

Having described my invention, what I claim as new, and desire to secure by Letters Patent, is—

20 The design for an air-chamber as herein shown and described.

Signed at New York, in the county of New York and State of New York, this 7th day of February, A. D. 1899.

30 JAMES J. LAWLER.
